TABBING CRADLE

Irving J. Foy, Denison, Iowa

Application August 5, 1936, Serial No. 94,441
Renewed August 13, 1937

9 Claims. (Cl. 11—1)

The present invention relates to a tabbing cradle and has for an object to provide a device in which paper and the like may be held while performing the operation of tabbing.

Another object is to provide a device which is adjustable to handle various paper sizes for tabbing.

A further object is to provide a device in which a plurality of stacks of paper may be handled simultaneously.

Further objects include ready changing of sizes for handling various papers, the provision of devices for clamping the paper which may be readily operated and which may be used in conjunction with ordinary printer's furniture blocks to adapt them to various sized stacks of paper.

It is the custom among printers and bookbinders to hold stacks of paper for tabbing, sewing or similar operations by merely laying the stack on any flat surface and placing suitable weights on the top of the stack to hold it during the operation. It will be recognized that this is a crude and unsatisfactory method of handling stacks of paper particularly when they reach a considerable height. Even more difficulty is experienced when the paper is of different thicknesses at various places, as for instance where a perforation is run across part of the paper. This situation is frequently met when tickets are being tabbed. In such a case it is almost wholly impossible to tab a large stack at once as the stacks are uneven and topple over.

The present invention contemplates a device which provides compartments of various selected sizes corresponding to the common sizes of paper handled. The paper is inserted into these compartments with the edge to be glued or sewed projecting outwards and thereupon pressure is placed on the stack to clamp it and hold it securely during the operation.

With the foregoing and other objects in view, the invention will be more fully described hereinafter, and will be more particularly pointed out in the claims appended hereto.

In the drawings, wherein like symbols refer to like or corresponding parts throughout the several views.

Figure 1 is a perspective view of a tabbing cradle made according to the present invention.

Figure 2 is an end elevation looking at the right end of Figure 1.

Figure 3 is a transverse vertical section taken on the line 3—3 of Figure 1.

Figure 4 is a transverse horizontal section taken

on the line 4—4 of Figure 1 showing paper in clamped position in the cradle.

Figure 5 is a front elevation of a cradle showing two paper holding compartments and paper clamped therein.

Figure 6 is a front elevation of a cradle shown clamping a large vertical stack of paper.

Figure 7 is a perspective view of a series of back boards employed in making up the paper compartments, and

Figure 8 is a perspective view of a shelf or tray used in conjunction with the back boards to form the compartments.

Referring now to Figure 1 the present embodiment of the invention as there seen comprises a base-board 10 having at one end an end board 11 and at the other an end board 12. The end boards 11 and 12 are secured to the base-board 10 by any means possessing the requisite strength to resist action of clamping. Between the end boards 11 and 12 at their upper edges and near the front of the cradle is placed a tension bar 13. The rear edges of the end boards are connected and braced by means of suitable bars 14. The lower front edge of the base-board 10 is preferably provided with legs 15 which serve to elevate the front or working side of the cradle and so make it more accessible.

As will be seen in Figure 1 the end board 11 is provided on its inner face with a series of spaced vertical grooves or guides 16, seven in number in the present instance. These grooves are located with respect to the front of the cradle according to the depth of paper stock expected to be handled. The end board 11 likewise has spaced horizontal grooves or guides 17 which are located to accommodate various widths of paper.

As will be seen in Figure 3 the end board 12 is provided with corresponding guides 16 and 17. The right end board 12 has located in a vertical line near its front edge a series of compressing screws 18 which pass through the board and are operable from outside of the cradle. These screws 18 are positioned so that one lies between each pair of guides 17 and one lies between the top and the uppermost groove and another between the bottom and the lowermost groove. The purpose of this location will appear hereafter. The tension bar 13 across the top of the cradle is provided with a pair of compressing screws 19 which are adapted to exert pressure in a downward direction.

The cradle is provided with a set of back boards 20 of various sizes one corresponding to the height of each of the grooves 17 above the base-board 10

and one corresponding to the total depth of the cradle. These back boards 20 are adapted to be slid into the guides 16 to define the depth of a paper compartment. The cradle has also a series 5 of trays 21 adapted for sliding in the guides 17. These trays 21 are provided in a variety of sizes corresponding to the distances of the guides 16 from the front edge of the cradle. These trays 21 define the height of the compartments formed. 10 Now referring to Figure 5 the cradle is seen with a tray 21 placed in the intermediate guide 17 so that the width of the cradle is divided in two. As seen from the top in Figure 4 a back board 20 is inserted in the third guide 16 from the rear of the cradle; that guide 16 being chosen which will bring the edge of the paper to the open side of the cradle so that it may be tabbed. A short 15 stack of paper 22 is placed in the upper compartment thus formed and is held in place by the compressing screws 18 from which it is spaced by suitable sizes of printer's blocks or the like 23. In the lower compartment of the cradle is placed a larger stack of paper 24. The size of this stack brings the end so near to the compressing screws 20 that the large block 23 can be eliminated. It will be readily seen that the stacks of paper 22 and 24 are held in perfect alinement during the complete tabbing operation permitting the operation to take place more rapidly and accurately 25 than it was possible by the older means employed by printers or bookbinders.

When the cradle is to be used for holding very large sheets of material it may be advantageous or necessary to stack the sheets vertically as 30 shown in Figure 6 instead of laying them on edge. In Figure 6 a stack 25 of sheets of large dimensions is clamped in the cradle. In this case the compressing screws 19 of the tension bar 13 are employed and a plate or block 26 is interposed 35 between the screws 19 and the top of the stack for the purpose of equalizing the pressure of the screws and preventing the injury of the upper sheets of the stack. In this case the base-board 10 of the cradle provides the bottom of the paper 40 compartment while the longest back board 20 is employed in the guide 16 which is suitable to 45 position the working edge of the paper properly.

It is to be noted that the tabbing cradle may 50 be made of any suitable material and any construction may be employed which will provide the requisite sturdiness. If the cradle is made of wood it is preferred to line the guides 16 and 17 with metal to reduce friction and absorb wear. It is also preferred to place corner caps 27 on the 55 leading corners of the back boards 20 and the trays 21. The purpose of these caps is dual, the metal absorbs wear and reduces friction and also prevents jamming in the guides.

The structure of the cradle itself particularly 60 as regards the bracing bars 16 and the top structure are susceptible of wide variation. Thus, if desired the back may be made solid and the top may be provided with further bracing.

With the above described cradle it is possible 65 to tab more than one stack of paper as shown in Figure 5. In addition to this, because of the various sizes of back boards 20 and trays 21 provided, papers of different sizes may be clamped, the sizes of the compartments being varied to 70 suit.

The cradle is not at all limited as to size. Thus it may be made to accommodate small 75 tickets or cards or used in the binding of small tablets or books. On the other hand, the size

board or similar stock on which these operations are to be performed.

It is obvious that various changes and modifications may be made in the details of construction and design of the above specifically 5 described embodiment of this invention without departing from the spirit thereof, such changes and modifications being restricted only by the scope of the following claims.

What is claimed is:

1. A tabbing cradle comprising a frame, means 10 including guides and partitions dividing the frame to form compartments of various sizes to receive different sizes of paper, and means for clamping paper in the compartments so formed 15 to hold the paper in position for tabbing.

2. A tabbing cradle comprising a frame having 20 end boards provided with spaced sets of horizontal and vertical guides, partitions of various sizes inserted into certain of said guides to provide paper receiving compartments of various sizes, and clamping means applicable to paper in any of the paper receiving compartments.

3. A tabbing cradle comprising a frame having 25 end boards provided with horizontal and vertical guides, partitions inserted into certain of the guides to form compartments, and a tensioning bar at the top of the frame having means thereon for exerting downward pressure on paper to hold the same for tabbing.

4. A tabbing cradle comprising a frame having 30 end boards provided with spaced sets of horizontal and vertical guides, partitions of various sizes inserted into certain of said guides to form paper receiving compartments of various sizes, and compressing means in an end board adapted to 35 apply horizontal clamping pressure to paper in a compartment.

5. A tabbing cradle comprising a frame having 40 opposite end boards provided with series of spaced horizontal and vertical guides, partitions of various sizes inserted into certain of said guides to provide compartments for receiving paper, and a series of vertically spaced apart compressing screws in an end board disposed to 45 lie between horizontal guides thereon and adapted to exert horizontal clamping pressure on paper in a compartment to hold the same for tabbing.

6. A tabbing cradle comprising a frame, means 50 for dividing the frame into various sized paper holding compartments, and means for exerting clamping pressure on paper in said compartments.

7. A tabbing cradle comprising a base-board, 55 opposite end boards rising from the ends of the base-board, bracing bars between the back edges of the end boards, a tension bar at the top between the upper front edges of the end boards, said end boards having spaced horizontal grooves 60 corresponding in distance from the top of the cradle to the various sizes of paper to be handled and also having spaced vertical grooves corresponding in distance from the front of the cradle 65 to the various sizes of paper to be handled, back boards of varying heights inserted into certain of the said vertical grooves, trays of varying depths inserted into certain of the said horizontal grooves, said back boards and trays when in position in the grooves providing paper receiving 70 compartments of varying sizes, and means for clamping paper in position in said compartments.

8. A tabbing cradle comprising a base-board, 75 opposite end boards rising from the ends of the base-board and having thereon spaced sets of horizontal and vertical guides, back boards of 75

5 varying heights inserted into certain of the vertical grooves, trays of varying depths inserted into certain of the horizontal grooves, braces at the top and back of said end boards, said back
10 boards and trays adapted to define paper holding compartments of varying sizes, means on an end board for exerting clamping pressure on paper in one of said compartments, and legs on the front edge of said base-board for tilting the cradle to elevate and make more accessible the working edges of paper in said compartments.

9. A tabbing cradle comprising a base-board, opposite end boards rising from said base-board

and having spaced sets of horizontal and vertical guides, various sizes of back boards inserted into certain of said vertical guides, various sizes of trays for insertion into said horizontal guides, said back boards and trays when in position in said guides forming paper receiving compartments of various sizes, metal caps on the corners of the leading edges of said back boards and trays to reduce friction in said guides and to prevent jamming of the back boards and trays therein, and clamps on an end board for holding paper in one of said compartments.
